UNITED STATES PATENT OFFICE.

CLYDE C. BROWN, OF SPOKANE, WASHINGTON.

SUBMARINE TORPEDO.

1,287,863.

Specification of Letters Patent. Patented Dec. 17, 1918.

Application filed March 25, 1918. Serial No. 224,550.

To all whom it may concern:

Be it known that I, CLYDE C. BROWN, a citizen of the United States, residing at Spokane, in the county of Spokane and 5 State of Washington, have invented certain new and useful Improvements in Submarine Torpedoes, of which the following is a specification.

The present invention relates to improvements in submarine torpedoes, and particularly to that type or class of such devices as are released or freed and actuated by the action of a passing vessel. The invention is especially adapted for the destruction 10 of submarine, or submersible war vessels, and to this end the invention utilizes a cable or trackway, forming a barrier against which the enemy vessel is calculated to strike, and actuate the propelling mechanism of the torpedo through the consequent movement of the cable or trackway which cable forms a guide to the object 15 to be destroyed.

In the accompanying drawings one complete example of the physical embodiment 20 of the invention is illustrated, wherein—

Figure 1 is a diagrammatic view showing the submerged torpedo and its supporting cable or trackway, with a non-submersible 25 vessel passing over the barrier, and showing also a submerged vessel about to strike the cable or barrier.

Fig. 2 is a diagrammatic view showing a submerged vessel as having struck the barrier or cable, buoyant supports for the cable being displaced by the moving torpedo, and the torpedo traveling toward its destination and guided over the suspended cable.

Fig. 3 is an enlarged, fragmentary view 30 showing a resilient or elastic connection and a frangible connection between the cable and a buoy and the torpedo and a buoy, for actuating the propeller.

Fig. 4 is a sectional detail of the torpedo 35 and its connections.

Fig. 5 is a broken, bottom plan, of the front end of the torpedo.

Fig. 6 is a perspective detail of one of the cable supporting buoys.

Fig. 7 is a detail of the cable clutch of 40 one of the cable supporting buoys, showing the detachable feature of the buoy.

In utilizing the invention a cable 1 is stretched, at a suitable depth, in the water, 45 between the two stay cables 2, 2, which in normal condition, stand vertical, and

are attached to the anchors 3, 3, resting on the bottom of the sea. Large buoyant floats or spherical buoys 4, 4' connect the stay cables with the suspending cable, 60 and a sufficient number of detachable buoys 5 are designed to support the cable at the proper depth. Each of these detachable buoys is provided with a clutch device 6 by which the buoy is held below the surface 65 of the water, and a release lever 7 is pivoted at 8 to each of these detachable buoys, and by the proper manipulation of these levers, the buoys 5 are successively detached, and then rise to the surface of 70 the water to indicate the travel of the torpedo.

At one end of the supporting cable, and connecting it with the buoy 4', is a contractile spring 9 and a cord 10 that are 75 factors in freeing the torpedo 11. The torpedo is made up of the usual casing, and extending longitudinally therethrough is a central tube 12 through which passes the cable 1, and at the front of the torpedo 80 the usual charge or explosive mixture is indicated at 13. The detonators 14 are arms that project beyond the front of the torpedo, and are pivoted at 15 on the outer surface of the torpedo casing, with their firing pins 85 extending, operatively, into the explosive charge and the charge is exploded when the detonators, one or more, strike an object with sufficient impact.

The torpedo is propelled through the instrumentality of an air motor 16, located at 90 the stern of the torpedo, when the valve 17 is withdrawn from the ports 18, and the motor has an inlet motive fluid port 19 and an outlet port 20 as shown. The valves or 95 ports 18 that are uncovered, when the valve 17 is pulled open by the cord 10, are openings in a tubular journal 21 located in the stern bearing 22, and the propeller 23 is revoluble with this tubular journal 21 that is 100 revolved in its bearings by the motor to drive the torpedo. As the torpedo proceeds it successively detaches the buoys 5 by reason of the nose of the torpedo contacting 105 with the buoy fastening, to engage the release lever 7 to open the clutch 6 to free the buoys. The operation of the device is obvious. In Fig. 2 it is assumed the submarine vessel S has struck the cable 1 and the impact has stretched the spring 9. Only 110 a slight movement is necessary to open the ports 18 and this movement of the valve 17

is caused when the resiliency of the spring permits its elongation. The cord 10, being non-stretchable, holds the valve 17 to which it is attached, and the slight movement of the torpedo on its support causes the unseating of the valve 17. Compressed air in the casing 11 now rushes through the inlet 19 of the motor, the motor is actuated and by it the torpedo is propelled toward its target. In the initial movement the valve 17 is withdrawn and the cable and its spring 9 remain suspended, taut, for a trackway or guide direct to the vessel that has struck the cable. In its course, the torpedo frees the buoyant devices 5, successively, as indicated in Fig. 2, and when the arms or prongs 14 encounter the object of attack, the charge is exploded in the torpedo in close proximity to the target.

20 I claim:—

1. The combination with a suspended flexible support having an elastic portion, of a torpedo movable and guided on the support, a releasing device on the torpedo, a non-elastic member connected with the releasing device and adjacent the elastic portion and connected with the support, whereby the torpedo is started when the support is flexed.
2. The combination with a submerged cable having an elastic portion and its end anchoring cables, of detachable buoyant supports for the cable, a torpedo movable and guided on the cable, a releasing device on the torpedo, means for detaching the buoyant supports, an inelastic member in proximity to the elastic portion and with its re-

spective ends attached to the releasing device and cable.

3. The combination with a submerged, suspended cable having an elastic portion and an inelastic member paralleled therewith having one end fixed, of a torpedo provided with a tubular guide member surrounding the cable and movable thereon, and a releasing device on the torpedo to which one end of the inelastic member is attached, for the purpose described.

4. The combination with a submerged cable having buoyantly supported anchoring cables and detachable marking buoys, of an elastic portion at one end of the cable and an inelastic member parallel therewith having one end fixed, a torpedo having a central tubular guide surrounding the cable, a releasing device for the torpedo, and a connection between the elastic portion and said device for the purpose described.

5. The combination with a guide cable suitably supported, of a torpedo movably supported thereon, and propelling means for the torpedo, of detachable marking devices on the cable, and means on the torpedo for successively detaching said devices.

6. The combination with a guide cable suitably supported, of a torpedo having a central tubular guide surrounding the cable and propelling means for the torpedo, detachable buoyant marking devices on the cable, and means on the torpedo for detaching said devices.

In testimony whereof I affix my signature.

CLYDE C. BROWN.
